United States Patent Office.

FRIEND THRALL, OF OSHKOSH, WISCONSIN, ASSIGNOR TO HIMSELF AND A. B. THRALL, OF SAME PLACE.

Letters Patent No. 91,054, dated June 8, 1869.

IMPROVED DOUGH-KNEADER.

The Schedule referred to in these Letters Patent and making part of the same.

To all whom it may concern:

Be it known that I, FRIEND THRALL, of the city of Oshkosh, State of Wisconsin, have invented a new and improved Machine for Kneading Bread and Moulding Pastry; and I do hereby declare that the following is a full and exact description thereof, reference being had to the accompanying drawings, and to the letters of reference marked thereon, making a part of this specification.

The nature of my invention consists in providing a table with a reversible top or mould-board, that will slide right and left on rollers in the direction of its length, and surmounted with supports, located centrally to the length of the table, with bearings to maintain an adjustable roller contiguous to the sliding mould-board, and a vibratory dredge-box or flour-duster immediately above, the roller to be of any convenient form required for kneading the dough, or reducing the same into thin sheets for pie-crust, crackers, cake, and other similar purposes.

Figure 1 is a longitudinal section in a vertical plane.

Figure 2 is a vertical cross-section.

Figure 3 is a side elevation of the roller-support, with a fragment of the table.

Figure 4 is a perspective view of the table-top, shown in a reverse position as a mould-board.

Figure 5 is a perspective view of a smooth roller.

Figure 6 is a perspective view of a knuckled roller. A A is a table.

B is a reversible top, the one side used as a mould-board, the opposite side as an ordinary table-top.

C, fig. 1, is a corrugated kneading-roller, with a crank, C'.

D is a dredge-box, hinged to supports A' A', that receives an oscillating motion through the arm f, resting on a corrugated surface of the roller beneath.

d is a button to disconnect the arm f from the corrugated roller.

E is a disk that supports the mould-board when in service.

E' E' are supplementary disks, that support and allow the mould-board to slide.

A' A' are supports, with bearings for rollers.

k k are bearings for rollers.

i and i' are a hinged cap and button, that allow the roller to be conveniently taken out or changed.

l is a rod, secured at the bottom to the support A', and serves to maintain the bearing k in position.

g g are adjusting-screws, connected with bearings k k.

C, fig. 5, is a smooth roller, for reducing to sheets, with a corrugated end, n.

C, fig. 6, is a knuckled roller, the base of which is polygonal in form, usually six-sided, and with each side set with a row of half-ball-shaped disks, and has a corrugated end, n, and may, at option, be used in place of C, fig. 1, for kneading.

Having described the parts of my invention, I will now proceed to describe its operation for kneading bread.

The top being adjusted, with mould-board side up, as seen in fig. 4, a kneading-roller being set in the supports A' A', and adjusted relatively to the mould-board by the set-screws g g and the dredge-box D, adjusted through the arm f to rest on the corrugated surface of the roller, the dredge-box is supplied with flour, and the sponge is placed on the mould-board, to be passed, turned, and repassed beneath the roller, the rollers and mould-board being dredged with flour from the box D to prevent sticking, until the dough is brought to a proper consistency.

For pie-crust, set and adjust the roller C, fig. 5; pass the dough beneath the roller until reduced to a proper thickness.

The supports A' may be permanently or temporarily secured relatively to the mould-board, or to a mould-board supported by a table, whereby the respective parts of the machine may be readily taken apart and stored in the body of the table, or otherwise, and the table serve complete for ordinary use.

The table may likewise be provided with one or more table-leaves, all without departing from the scope of my invention.

For greater convenience in using the mould-board, it may be slid in the direction of its length until one end rests under the kneading-roller, where it may be secured through the adjusting-screws, by dropping the roller until it rests firmly on the end of the mould-board, thus allowing free use of the whole size of the mould-board for pastry or other purposes.

What I claim as my invention, and desire to secure by Letters Patent, is—

1. A reversible sliding mould-board and table-top B, as described, arranged relatively to either kneading or reducing-rollers, the latter having bearings in the supports A' A', and provided with adjusting-screws g g, traverse-bearings k k, and hinged box-caps i i, substantially as described, for the purposes set forth.

2. The roller C, fig. 6, provided with a crank, C', and constructed substantially as described, when arranged, relatively to the supports A' A' and sliding mould-board B, as and for the purposes set forth.

3. The dredge-box D, arranged, relatively to roller C and mould-board B, as and for the purposes set forth.

4. Box D, provided with button d and arm f, arranged, relatively to a roller beneath, substantially as and for the purposes set forth.

FRIEND THRALL.
